UNITED STATES PATENT OFFICE.

ALRED GORDON COLLEY, OF RICHMOND, VIRGINIA.

INTERNAL-COMBUSTION ENGINE.

1,165,494.

Specification of Letters Patent. Patented Dec. 28, 1915.

Application filed September 8, 1914. Serial No. 860,720.

To all whom it may concern:

Be it known that I, ALRED G. COLLEY, a citizen of the United States, residing at Richmond, in the county of Henrico and State of Virginia, have invented a new and useful Internal-Combustion Engine, of which the following is a specification.

The present invention relates to improvements in internal combustion engines, one object of the present invention, being the provision of a stationary engine in which the power cylinder and gas admitting and compression chamber are formed integral, said latter chamber being disposed transversely at one end of the power cylinder and being provided with removable plugs one of which carries the spark plug while the others of which permit free access for the removal and grinding of the intake and exhaust valves.

A further object of the present invention, is the provision of an internal combustion engine, the cylinder of which is surrounded by a jacket having an enlarged portion with an open mouth, said jacket and enlarged portion being adapted to contain water for cooling the cylinder, thus rendering it unnecessary to provide a circulating pump for causing the water to circulate, the heat from the cylinder causing the proper circulation within the tank.

With the foregoing and other objects in view which will appear as the description proceeds, the invention resides in the combination and arrangement of parts and in the details of construction hereinafter described and claimed, it being understood that changes in the precise embodiment of the invention herein disclosed can be made without departing from the spirit of the invention.

In the drawings—Figure 1 is a longitudinal sectional view through the cylinder and water jacket and chamber of the present invention, the same being taken through the intake valve thereof. Fig. 2 is a cross section taken on line 2—2 of Fig. 1. Fig. 3 is a section taken on line 3—3 of Fig. 2.

Referring to the drawings, the numeral 1 designates the power cylinder which is provided at its end, with the integral transversely disposed elliptical chamber 2, having the interiorly threaded port or opening 3, in the axial line thereof and also coaxial with the cylinder 1. Insertible within this interiorly screw threaded opening 3 is the

plug 4 which carries the spark plug 5. Thus by removing the plug 4, access may be had to the reduced chamber 2 of the present engine.

Formed in the upper portion of the walls of the reduced chamber 2, as clearly illustrated in the drawings, is an interiorly screw threaded opening 4 for the reception of the removable plug 5, while at the opposite side or parallel therewith, as clearly illustrated in Fig. 2, is an interiorly screw threaded opening 6, fitted with the removable plug 7. These plugs 5 and 7 constitute a means for permitting of the grinding, inserting and removal of the respective puppet valves 10 and 16, as will later appear.

The exhaust port 8 of the present engine is located to communicate through the valve seated portion 9 into the reduced chamber 2, said valve seated portion 9 being controlled by the puppet valve 10, whose stem 11 is slideable through the adjustable sleeve 12 which is mounted in the interiorly threaded aperture 13 as illustrated in Figs. 1 and 2. The intake port 14 is in communication with the valve seated port 15 controlled by the puppet valve 16, the stem 17 of which is slidably mounted in the sleeve 18 adjustably mounted in the interiorly screw threaded opening 19 and by this means both the valve stems 11 and 17 are coaxial with the respective openings 4 and 6, and are thus mounted for parallel movement. By this means no strain is placed upon the stems as would be the case where the valves are through the side of the chamber as both have vertical straight line movements.

The mechanism for operating both valves is similar, being shown as operating the intake valve in Fig. 1. To accomplish this, the spring 20 surrounds the lower end of the stem 17 and is adjusted by means of the adjustable bushing or cap 21 adapted to be engaged by the adjustable means 22 carried in the free end of the lever 23. This lever 23 is journaled at 24 in the base 25 of the engine, and carries a roller 26 at its opposite end. This roller is disposed for engagement by the cam 27 mounted upon the transverse shaft 28 fixed to the gears 29 and 30 which are operated in timed relation to the crank shaft 31. As usual the crank shaft 31 is connected to the piston 32 and to the power cylinder.

As clearly illustrated, instead of having a water circulating system as usual to cool

the cylinder 1 and the chamber 2, a water reservoir 34 having the enlarged mouth 35 to permit of the escape of steam therefrom and to prevent any excess pressure within 5 the same is disposed to surround the cylinder 1 and portion 2 thereof, the reduced portion of the cylinder at 36 surrounding the cylinder 1 adjacent the inner end thereof. Thus the reservoir or tank 34 is prop- 10 erly filled with water and as the lower portion of the water is heated through the cylinder 1 and chamber 2, the same rises to the top and thus creates a circulation within the tank. By this means the usual pump and 15 other water circulating means is dispensed with, thus producing an exceedingly simple and inexpensive structure.

By arranging the valves as illustrated in Fig. 2, it is apparent that the same are readily accessible through the opening 35 of the water tank 34 and that the valves may be readily inserted and ground or removed when desired.

What is claimed is:

An internal combustion engine, includ- 25 ing a power cylinder having a reduced transversely disposed chamber at one end, said chamber and cylinder being disposed horizontally, said reduced chamber being provided with an intake and an exhaust 30 port and with two oppositely disposed alined openings, plugs for sealing said openings, and an integral water jacket, surrounding the greater portion of the cylinder and also the reduced chamber, the last 35 mentioned openings being open into the jacket and said jacket being provided with a hand hole opening to permit access thereto.

In testimony that I claim the foregoing as my own, I have hereto affixed my signature 40 in the presence of two witnesses.

ALRED GORDON COLLEY.
